Inventor:

Isaac A. Wesson

UNITED STATES PATENT OFFICE.

ISAAC A. WESSON, OF WINGO, KENTUCKY.

CHURN-POWER.

No. 839,349.

Specification of Letters Patent.

Patented Dec. 25, 1906.

Application filed July 25, 1906. Serial No. 327,760.

To all whom it may concern:

Be it known that I, ISAAC A. WESSON, a citizen of the United States, residing at Wingo, in the county of Graves and State of Kentucky, have invented a new and useful Churning-Machine, of which the following is a specification.

My invention relates to improvements in churn-powers. Its object is to effect the ready actuation of the churn-dasher either by foot or hand power, the returning stroke being automatic; to reduce to the minimum friction; to facilitate the working of the machine; to lessen the effort required to accomplish the churning operation, and to carry out these ends in a simple, expeditious, and effective manner.

Said invention consists of certain structural features or instrumentalities substantially as hereinafter fully disclosed and specifically pointed out by the claims.

In the accompanying drawing, illustrating the preferred embodiment of my invention, the figure represents a perspective view of the same.

In the disclosure of my invention I suitably mount upon a base of any required construction a receptacle or cylinder for holding the cream or milk for conversion into butter, within which may be placed any form of dasher having a staff or handle, as seen. To said staff in its elevated position is suitably connected or fixed the outer end of the horizontal arm of a right-angled pitman-rod C, preferably as disclosed, said end being recurved or bent upon itself to form a loop or staple-like terminal a to receive said staff and having the two legs of the thus formed staple passing through a cross-piece or clamp-bar D, clamping said staff in position by a nut b, screwed upon one of said legs against said staff. This pitman-rod has its vertical or pendent portion suitably secured near its lower end to a sliding cross-bar F, said lower end portion being extended horizontally and rearward, as at J, with its extreme rear end upturned to provide for the suitable application of the foot thereto, as when it may be desired to employ foot-power for its actuation in thus operating the churn-dasher.

The cross-bar or slide F is guided in its vertical movement by an upright preferably inverted-U form of frame B, suitably secured in fixed position at the lower ends of its lateral members to the base A, said slide or

cross-bar being provided upon its forward side with loops or eyes c, receiving said lateral members of said frame B. Said vertical or pendent portion of the pitman-rod C also passes through and is guided in its movement by an apertured lug E, fixed to the upper horizontal portion of the frame B. Said pendent or vertical portion of the pitman-rod C has attached to it near its lower end the lower ends of preferably two compactly-coiled springs e, the upper ends of said springs being suitably secured to the upper horizontal portion of the frame B, whereby as downward pressure is exerted upon said pitman-rod the springs e will be expanded or stressed, and upon the removal of such pressure the recoil action of said springs will automatically restore said pitman-rod to its elevated position, together with the dasher-rod.

The cross-bar or slide F has suitably connected thereto by links or rods d the forwardly-projected lateral bars of a treadle I, the rear ends of said lateral bars being hinged or articulated, as at R, to a rearward extension of the base A, preferably as shown. To said treadle is also suitably connected or pivoted the lower end of a preferably cross-pin-equipped lever or handle S for the convenient actuation by hand-power of said treadle, and accordingly the operating of the churn-dasher in such manner.

A suitably-constructed fly-brush D' is applied to the dasher-staff, having the downward-bent ends of its ring-like wire frame 90 detachably inserted in between said staff and the clamp-bar D.

I claim—

1. A device of the character described, having a downward-extending pitman-rod 95 effective for attachment to a dasher-staff, guiding means for said pitman-rod, said rod having its lower end extended rearward and adapted to permit of the application of downward pressure thereto, and means for imparting the return stroke to said pitman-rod.

2. A device of the character described, having a downward-extending pitman-rod, having its lower end extended rearward and adapted to permit of the application of downward pressure thereto, means for effecting the automatic return stroke of said pitman-rod, an upright fixed frame, a cross-bar fixed to said pitman-rod, means for the guidance of said cross-bar, and foot-actuated means 105 110

linked or connected to said cross-bar, said pitman-rod adapted to be connected to a dasher-staff.

3. A device of the character described, having a right-angled downward-extended pitman-rod effective for attachment to a dasher-staff and having fixed thereto a transverse bar provided with guide eyes or loops, a fixed upright frame having its lateral members passing through said eyes or loops, means for applying downward pressure to said transverse bar and means for automatically returning said pitman-rod to its elevated position.
4. A device of the character described, comprising a right-angled pitman-rod, an upright fixed frame having a guiding-lug for said pitman-rod, means for imparting automatically the return stroke to said pitman-rod, a transverse bar fixed to said pitman-rod and having guide eyes or loops receiving the lateral members of said upright frame, and means connected or linked to said transverse bar, for actuating said pitman-rod.
5. A device of the character described,

comprising a right-angled downward-extended pitman-rod having a staple-like terminal equipped with a nut and a clamp-bar for the attachment thereof to a dasher-staff, a fixed upright frame having guiding means for said pitman-rod, a transverse bar fixed to said pitman-rod and provided with means for its guidance upon the lateral members of said upright frame, and means connected or linked to said transverse bar for actuating said pitman-rod by hand or foot power.

6. A device of the character described, comprising a right-angled pitman-rod effective for attachment to a dasher-staff, means for guiding said pitman-rod in its movement, springs connected to said pitman-rod and the guiding means therefor effective to impart the return stroke to said pitman-rod, means for actuating said pitman-rod connected to a transverse bar having eyes or loops receiving said pitman-rod-guiding means.

ISAAC A. WESSON.
